mesne assignments, to B. G. Corporation,
Cleveland, Ohio, a corporation

Application July 21, 1933, Serial No. 681,521

5 Claims. (Cl. 248—13)

This invention relates to a stand for supporting a motor operated device such as, for instance, an eyebrow plucking and arching device.

An object of the present invention is to provide a stand of the type referred to which is simple in construction, easily handled and conveyed from place to place, and inexpensive to manufacture.

A further object of the invention is to provide a stand of fool proof construction which in the event that the stand is upset or knocked over will not result in damage either to the stand or the device which is supported thereon.

With the objects above indicated and other objects hereinafter explained in view the invention consists in the construction and combination of elements hereinafter described and claimed.

Referring to the drawing:

Fig. 1 is a side elevational view of the stand and device embodying the present invention;

Fig. 2 is a rear elevational view of the stand and device shown in Fig. 1;

Fig. 3 is a top plan view of that shown in Fig. 1;

Fig. 4 is a fragmentary view in elevation of the upper portion of the stand showing the motor guard and stop;

Fig. 5 is a cross-sectional view taken on line 5—5 of Fig. 3 showing details of the construction on an enlarged scale;

Fig. 6 is a cross-sectional view taken on line 6—6 of Fig. 5 showing the stops limiting the movement of the motor about its vertical axis.

In the drawing the stand embodying the present invention comprises a base 10 preferably in the form of a substantially triangularly shaped casting having a circular bottom portion 11 and extensions or lugs 12 formed integral with the under surface thereof by which the stand is adapted to be supported upon the floor or other suitable supporting structure. The upper end of the base 10 is provided with a vertically extending opening 13 within which is secured the lower end of a tubular upright member 14 of any desirable height and diameter depending upon the purpose for which the stand is to be used.

A support 15, preferably of circular formation, has a substantially flat upper surface 16 which is positioned transversely with respect to the upright 14. On the under side of the support 15 is a depending extension 17, preferably formed integral with the support 15 and axially thereof. This extension 17 is adapted to fit within the upper end of the tubular upright 14, as clearly shown in Fig. 5, and is secured against accidental disengagement by means of a bolt 18. In the support 15 is an axial opening 19 which extends entirely through the extension 17 and rotatably receives therein a rod 20. The upper end of the rod 20 is serrated at 21 and is secured within an opening 22 provided in the lower portion of a yoke 23. This connection may be a force fit con-

nection in order to facilitate ready assembly. The yoke 23 has a flange 24 upon its under side extending around the opening 22 and engages the upper surface 16 of the support 15 to maintain the yoke in proper position, the yoke, of course, being rotatable with the rod 20. The lower end of the rod 20 is provided with a transverse opening within which a pin 25 is secured, the pin having extending ends which are adapted to engage with oppositely disposed stops 26 provided upon the lower end of the extension 17, thus limiting the rotary movement of the yoke 23 about the axis of the rod 20 and at the same time being engageable with the end of the extension 17 to prevent accidental disengagement of the rod 20 with respect to the support 15.

A motor 27 of any desirable type is provided with a pair of oppositely extending trunnions 28 which are pivotally mounted within aligned openings 29 provided in the upper portions of the free ends or arms of the yoke 23. It will be noted that the axis about which the motor 27 pivots is transverse with respect to the axis about which the yoke 23 pivots, so that to a limited extent the motor 27 has a substantially universal movement within the limits required.

A hand grip member 30, preferably of inverted U-shape, has its lower ends extending through openings provided in the support 15, which ends are screw threaded to receive nuts 31 by which the free ends are secured to the support 15. The upper portion of the hand grip member 30 extends around the motor 27, as clearly shown in Fig. 2, and is substantially in longitudinal alignment with the axis of the rod 20. This hand grip member 30 is not only provided for the purpose of enabling the stand to be readily lifted and conveyed from place to place, but also functions as a stop to limit the oscillatory movement of the motor 27 about its pivotal axis, as shown in Fig. 4 and as will be more fully described hereinafter.

A flexible cable 32 has one end connected at 33 to an extension 34 of the motor housing, while the opposite end of the cable is connected with a housing 35 of any suitable operating tool. In the present instance the operating tool illustrated is of the tweezers type and is employed for plucking or arching eyebrows, however, it should be understood that the cable may be attached to any suitable tool for which the device is adapted. If further details of construction are desired with respect to the eyebrow plucking or arching device, reference should be made to the copending application of George S. Ubelhart and John E. McAllister, Serial No. 631,526, filed September 2, 1932, but as these details of construction do not form part of the present invention it is believed unnecessary to further explain the operation of this device per se.

Surrounding the cable adjacent its opposite

ends are coiled springs 36 which extend longitudinally of the cable for any desired distance, the ends of the springs adjacent the housings 33 and 35 being suitably secured. The purpose of the 5 springs is to protect the cable against sharp bends being made therein which would tend to not only destroy the cable, but interfere with the efficiency of the device.

The support 15 is provided upon one side with 10 a slot 37 which extends inwardly from the periphery of the support and an upwardly extending flange 38 extends around the slot and is formed integral with the support 15. The slot is of sufficient width to receive one of the springs 36 15 secured to the cable 32 and a band of rubber 39 is placed around the spring 36 and is adapted to engage with the upper portion of the flange 38 so as to be removably disposed therein. Diametrically opposite to the slot 37 is a similar slot 20 40 extending inwardly from the periphery of the support 15, but in this instance a flange 41 extends around the slot and downwardly, as shown in Fig. 5 and is formed integral with the under surface of the support 15. The housing 35 of the 25 operating tool is also provided with a band of rubber 42 which is removably disposed within the flange 41, while the spring 36 attached to the adjacent end of the cable 32 is adapted to be positioned within the slot 40. A rubber block 43 30 has a screw threaded stud and is adapted to be screwed into an opening provided in the support 15, which rubber block normally engages the housing 35 of the operating tool to maintain the same in proper position.

35 A toggle switch 44 is secured to the support 15 and is provided for controlling the operation of the motor 27. A flexible conductor 45 is connected to the motor 27 and has its other end extending through an opening 46 provided in the 40 support 15. One of the wires in this conductor 45 connects the motor with one side of the switch 44. An extension cord 47 extends through an opening 48 provided in the base 10 and upwardly within the upright 14 to adjacent its upper end 45 where it passes out through an opening 49. One wire of the extension cord 47 is connected with the other wire of the motor, while the other wire of the extension cord is connected to the opposite side of the switch. The free end of the extension cord is provided with the usual plug 50 for connection with any suitable source of current. A pair of clasps 51 are secured to the upright 14 in spaced relation and are adapted to receive the windings of the extension cord 47 55 when the latter is not in use.

As shown in Fig. 4 the hand grip member 30 is employed additionally as a stop to limit the oscillatory movement of the motor 27 about its 60 pivotal axis. This is to prevent the motor from rotating completely about its axis which would cause the conductor 45 to become twisted and possibly broken. However, this hand grip member 30 does not in any manner interfere with the efficient operation of the device.

65 Attention is directed to the fact that the diameter of the base 10 is somewhat greater than the diameter of the support 15 and the relationship should be such that the hand grip member 30, and the motor 27 with its associated parts will lie 70 within the apex of planes extending longitudinally of the stand and in contact with the peripheral edges of the base and support. This is of material importance in that it renders the stand fool proof and prevents any damage to the motor

or other parts of the apparatus in the event that the stand is accidentally knocked over. In other words, if the stand is accidentally knocked over it will rest upon the peripheral edges of the base 10 and support 15, thus preventing the motor 5 and operating parts thereof from contacting with the floor or their supporting structure.

While I have described the preferred embodiments of the invention it is to be understood that I am not to be limited thereto inasmuch as changes and modifications may be resorted to without departing from the spirit of the invention as defined in the appended claims.

Having thus described my invention, I claim:

1. A stand comprising a base, an upright having one end connected to said base, a support connected to the opposite end of said upright, a yoke pivotally mounted on said support, a motor pivotally mounted on said yoke, a flexible cable having one end connected to said motor, and means on said support for removably receiving the free end of said cable and the portion of said cable adjacent said motor.

2. A stand comprising a base, an upright having one end connected to said base, a support connected to the opposite end of said upright and provided with slots, a yoke pivotally mounted on said support, a motor pivotally mounted on said yoke, a flexible cable having one end connected to said motor, said cable being removably disposed within said slots when in inoperative position, and an extension cord connected to said motor.

3. A stand comprising a base, an upright having one end connected to said base, a support connected to the opposite end of said upright and provided with slots, a yoke pivotally mounted on said support, a motor pivotally mounted on said yoke, a flexible cable having one end connected to said motor, said cable being removably disposed within said slots when in inoperative position, a switch mounted on said support for controlling the operation of said motor, and an extension cord connected to said switch.

4. A stand comprising a base, an upright having one end connected to said base, a support connected to the opposite end of said upright and provided with slots, a yoke pivotally mounted on said support, a motor pivotally mounted on said yoke, a flexible cable having one end connected to said motor, said cable being removably disposed within said slots when in inoperative position, a switch mounted on said support for controlling the operation of said motor, an extension cord connected to said switch, and clasps 55 on said upright about which said extension cord may be wound when not in use.

5. A stand comprising a base, an upright having one end connected to said base, a support connected to the opposite end of said upright and provided with slots, a yoke pivotally mounted on said support, means for limiting the pivotal movement of said yoke, a motor pivotally mounted on said yoke, a flexible cable having one end connected to said motor, said cable being removably disposed within said slots when in inoperative position, a hand grip member secured to said support and extending around said motor, said member being adapted for engagement by said motor to limit the pivotal movement of the latter, a switch for controlling the operation of said motor, and an extension cord connected to said switch.

JOHN E. McALLISTER.
